US00D423096S

United States Patent [19]

Kwok

[11] Patent Number: Des. 423,096

[45] Date of Patent: ** Apr. 18, 2000

[54] **NASAL MASK CUSHION**[75] Inventor: **Philip R. Kwok**, West Pymble, Australia[73] Assignee: **ResMed Limited**, North Ryde, Australia

[**] Term: 14 Years

[21] Appl. No.: 29/076,269

[22] Filed: Aug. 25, 1997

[30] Foreign Application Priority Data

Feb. 25, 1997 [AU] Australia 577/97

[51] LOC (6) Cl. 29-02

[52] U.S. Cl. D24/110.1

CLAIM

The ornamental design for a nasal mask cushion, as shown and described.

DESCRIPTION

FIG. 1 is a top plan view of a nasal mask cushion of the present invention.

FIG. 2 is a bottom plan view of a nasal mask cushion of the present invention.

FIG. 3 is a front view of a nasal mask cushion of the present invention.

FIG. 4 is a perspective view of a nasal mask cushion of the present invention.

FIG. 5 is a rear view of a nasal mask cushion of the present invention; and,

FIG. 6 is a right side view of a nasal mask cushion of the present invention, the left side view being a mirror image thereto.
